J. A. SCOTT,
ADJUSTABLE STEEL HAME,
APPLICATION FILED JULY 27, 1916.

1,235,931.

Patented Aug. 7, 1917.

UNITED STATES PATENT OFFICE.

JESSE A. SCOTT, OF FULLERTON, NEBRASKA.

ADJUSTABLE STEEL HAME.

1,235,931.

Specification of Letters Patent. Patented Aug. 7, 1917.

Application filed July 27, 1916. Serial No. 111,675.

To all whom it may concern:

Be it known that I, JESSE A. SCOTT, a citizen of the United States, and resident of Fullerton, in the county of Nance and State 5 of Nebraska, have invented certain new and useful Improvements in Adjustable Steel Hames, of which the following is a specification.

The present invention relates to harness 10 and more particularly to new and useful improvements in adjustable hames.

The primary object of my invention is to provide in a simple and compact structure a new and improved type of hame having 15 adjusting means associated therewith, whereby to permit use of the hame in connection with various sizes of draft-animals and to adjust the trace connection, whereby to obtain the most efficient draft.

Another object of my invention is to provide a hame of the class described having 20 means associated therewith for increasing or decreasing the length of the hame.

A further object of my invention is to provide a hame of the class described which 25 is simple in construction, strong and durable, cheap to manufacture, and effective in operation.

Other objects and advantages to be derived 30 from the use of my improved adjustable hame will appear from the following detail description and the claims, taken with an inspection of the accompanying drawing, in which:

Figure 1 is an enlarged vertical sectional view of a hame embodying the improvements of my invention;

Fig. 2 is an enlarged transverse sectional view taken on the line 2—2 of Fig. 1; and

Fig. 3 is a similar view taken on the line 40 3—3 of Fig. 1.

Referring more particularly to the drawing, wherein similar characters of reference designate like and corresponding parts 45 throughout the various views, 1 designates the body of my improved hame, said body being tubular, elliptical in cross section, and tapering throughout its length, the lower free end thereof being provided with the 50 usual curved portion 2. I do not limit myself to the shape of the body 1 in cross section, since this body may be U-shaped or rectangular as desired.

For increasing the length of the body 1, I 55 provide a tapering section 3 receivable in the body 1 adjacent the upper free end

thereof, said section 3 having the upper free end thereof curved as at 4 and having the usual connecting link 5 carried thereby.

In order to maintain the section 3 in adjusted positions, I provide a relatively heavy plate 6 arranged within the section, said plate being engaged by a screw 7 as indicated at 8, said screw having a head 9 to which a wrench or the like may be applied for inserting and removing the screw. A slot 10 is formed in the body 1 to accommodate the shank of the screw 7, a plurality of rivets 11 being arranged transversely of the body, in spaced relation, adjacent 70 said slot, whereby to strengthen the body adjacent the slot and to receive the screw between any two of said rivets.

For adjusting the angle and height of draft I provide a tug clip 12 having an 75 opening 13 in the outer free end thereof to which the trace is to be connected. The lower part of the body 1 is provided with a slot 14 for accommodating the tug clip 12, a bolt 15 being arranged longitudinally 80 within the body, said bolt having the free ends thereof mounted in partitions 16 and 17, the enlargement 18 on the partitions 16 serving to receive the threaded end of the bolt 15 for a purpose which will hereinafter 85 appear.

A plurality of rivets 19 similar to the rivets 11 are provided, said rivets 19 extending transversely of the body 1 as shown to advantage in Fig. 3. The clip 12 is bifurcated on its inner end as indicated at 20 and formed with loops 21 through which the bolt 15 is adapted to engage, said bifurcated portion embracing one of the rivets 19.

A loop or strap 22 is arranged adjacent 95 the upper free end of the body 1 for accommodating the reins, said strap being secured in any desired manner. A ring 23 is carried in a U-shaped bracket member 24 adjacent the lower free end of the body 1, said ring 100 serving to accommodate the breast strap. Other necessary attachments may be associated with the hame of my invention, these attachments not being shown in view of the fact that they do not enter into the invention. 105

In using my improved hame it will be seen that by removing the bolt 15 the trace connector or tug clip 12 may be removed and adjusted to various positions relative 110 the body 1 in order to reach the desired angle and direction of draft, thus increasing

ing the efficiency of the hame and helping the draft-animal. The enlargement 18 is permanently fastened to the partition 16 to receive the threaded end of the bolt when 5 said bolt is inserted into position in the partitions 16 and 17.

From the above description taken in connection with the accompanying drawing, it 10 is thought that a clear and comprehensive understanding of the construction, operation and advantages of my invention may be had, and while I have shown and described the device as embodying a specific structure, I desire that it be understood 15 that such changes may be made in said structure as do not depart from the spirit and scope of the invention as claimed.

Having thus fully described my invention, what I claim as new and desire to set 20 cure by Letters Patent, is:

1. A hame of the class described including a body, said body having a slot longitudinally thereof adjacent the lower free end, a removable bolt arranged in said body parallel with the slot, a tug-clip slidably mounted 25 in said slot and engaging the bolt, and a

plurality of transversely arranged rivets carried by the body between the slot and bolt for holding the clip in various adjusted positions in said slot.

30

2. A hame of the class described, including a body, said body having a slot longitudinally thereof, adjacent the lower free end, a plurality of transversely arranged rivets adjacent said slot, a removable bolt arranged within said body adjacent said rivets, and a clip member having a bifurcated portion forming loops engageable with the bolt between said rivets.

35

3. In a hame of the class described, a 40 tubular body, said body having a slot adjacent the upper free end thereof, a plurality of transversely arranged spaced rivets located adjacent said slot, a section 45 slidable in said body adjacent the upper end thereof, and a bolt connected with said section and extending between two of said rivets for maintaining the section in adjusted position.

45

In testimony whereof, I affix my signature 50 hereto.

JESSE A. SCOTT.
